RESISTANCE UNIT

Filed Feb. 1, 1930

UNITED STATES PATENT OFFICE

JOHN L. MCWEENY AND WILLIAM D. MCCORD, OF CHICAGO, ILLINOIS

RESISTANCE UNIT

Application filed February 1, 1930. Serial No. 425,307.

Our invention relates to electrical devices and more particularly to resistance units and the method of making the same.

In the common radio receiving sets and other electrical apparatus of today, the construction of the various technical circuits require a number of fixed resistances for co-operation therewith. The resistance units required may vary from a small ohmage to a very large ohmage and the resistances necessarily are very frequently disposed at numerous suitable places.

An object of our invention is to provide a resistance unit which comprises a plurality of separate and independent resistance units all within the same container.

A further object of our invention is to provide a resistance unit which has the advantage of convenience in the location of various different resistances, and in addition, the construction of the unit of a minimum size, thus permitting the manufacturer to reduce overall size, whenever desirable.

A further object of our invention is to provide a resistance unit that is of minimum size and simplicity of construction in the case of resistances requiring a "ground" terminal.

The various elements of the completed resistance unit being each of an independent construction and having no electrical connection to the adjacent unit, may be constructed to fit every conceivable need in various circuits. The resistance elements may each be wound in an independent manner, that is to say, one element may be wound with 300 turns of .002 wire per inch, the second element may be wound at the rate of, perhaps, 500 turns per inch of .002 wire, and so on, each element being constructed to meet the particular requirements of that element within the circuit. Thus, it will be seen that it would be undesirable in many instances to take a number of taps from a single resistance unit for the different circuits. If, for

example, each of two independent circuits required a one thousand ohm resistance, in many instances this resistance could not be taken for each circuit, from the same two taps on the same unit. Obviously another 50 resistance unit of one thousand ohms must be provided.

It is our conception therefore, that any number of desired resistances may be provided, all placed in the same container, in an end-to-end relation, and located at a central point where desired. Thus, if any trouble should arise, the repair man could be saved considerable time and labor by reason of the fact that all the resistances are 60 located at this central point.

It is readily conceivable that two or three resistances disposed in the same container could, in most instances, provide for all the resistance requirements by the simple expedient of applying taps at suitable points on each unit.

The invention will be more readily understood by reference to the accompanying drawings, in which

Fig. 1 is a side elevation of a resistance unit constructed in accordance with my invention;

Fig. 2 is an end-section taken on the line 2-2 of Fig. 1;

Fig. 3 is a side elevation partly in section showing a plurality of resistance elements in the same device;

Fig. 4 is a plan view partly in section of the unit shown in Fig. 3;

Fig. 5 is a plan view of a modified form of our invention showing a ground connection;

Fig. 6 is a sectional view taken on the line 6-6 of Fig. 5;

Fig. 7 is a plan view partly in section showing a form of end terminal connection;

Fig. 8 is a perspective view of a terminal connection showing the method of application;

Fig. 9 is a fragmentary perspective view of the insulating shell;

Fig. 10 is a fragmentary perspective view of the metal can; and

5 Fig. 11 is a perspective view of a form of terminal connection.

By reference to the drawings, it will be seen that our invention comprises the strip 10 of fiber or any other suitable non-conductor of 10 electricity of any suitable length or width. Wound around the base 10 is the resistance wire 11 which is suitably wound with any desired size of wire, at a predetermined number of turns per inch. As best shown in Fig. 15 8 the terminal projections, indicated generally by the numeral 12 are applied over the wound wire 11 and firmly secured thereto. The terminal projections indicated generally at 12 are formed in the manner shown in Fig. 20 11 and comprise the upstanding wire connecting portion 13, the rebent portion 14, base portion 15 and wing 16. The terminals 12 are applied to the resistance element by merely inserting the wound resistance into the rebent 25 portion 14 and bending down the wing 16 into contact with the wire. The projections 12 are usually applied at the end of the element, and the application of the terminals 12 serves also to retain the ends of the resistance wire as 30 shown in Fig. 8. In the event a tap is desired to be taken on the resistance unit at any point between the ends thereof, the terminal is applied in the usual manner, the resistance of the adjacent sections being determined from 35 the marginal edge of the bases 15 of the respective terminal projections 12. After the terminal projections 12 have been applied to the wound resistance, the element is placed within a fiber or non-conducting shell 17, 40 best shown in Fig. 9. Thereafter the unit and fiber shell 17 are placed within the metal can 18, best shown in Fig. 10. The metal can 14 in the most desired form is formed as shown in Fig. 10, having the rebent portion 19 into 45 which the resistance unit carrying the terminal projections is placed. If desired for convenience with the use of dies, the outer can 18 may assume the shape of the insulating shell 17, which would fit thereon.

50 Thereafter, the assembly is subjected to pressure from a die and the sides of the shell 18 and insulator 17 are flattened as shown in Fig. 2. Thus, the completed device is ready for installation.

55 However, an object of our invention is to provide means for centralizing several of the resistances required in a circuit and to accomplish this purpose, we have devised the form shown in Fig. 3 which comprises two or more 60 units constructed as already described, set in an end-to-end relation, each element being independent, and there being no electrical connection between the adjoining elements. A plurality of independent elements having the 65 terminal projections 12, placed in suitable po-

sitions along the length of the resistance units and the various units are then placed within the insulator 17 and can 18 and the die then applied and the entire unit is thus fabricated.

70 Thus, several resistances adapted to provide, by means of taps, any of the various resistances required are contained in one device, and installed in a central or convenient place. For convenience, in securing the complete unit to a foundation or frame, a continuous strip of metal 20 is placed between the insulator 17 and the can 18. Thus when the sides of the can 18 are forced downward, the strip 20 is firmly secured and will resist tendency to be displaced. If desired, the securing portion at the end of the strip 20 may be stamped as a part of the outer can 18.

75 In some instances one terminal of the resistance unit desired is directly connected to a "ground" on the foundation or frame and a suitable form for this requirement is shown in Figs. 5 and 6. In this form the resistance is wound and the clip 12 is applied to one end. Instead of applying a terminal projection 12 to the opposite end as in the form shown in 80 Fig. 1, a small portion of the insulator 17 is removed as is shown at 21. An angularly bent ground connection 22 is applied over the insulator 17 and contacting a short portion of the wound resistance element 11 at one 85 end. Thus the connection 22 has a short area of contact with the resistance wire. The ground connection 22 is continued substantially the length of the unit as shown in Fig. 5 to insure against pulling out in case of rough 90 handling. As the element 22 is applied, a die closes the assembly and forces the end portion 23 of the metal can into flat contact against the connection 22. The balance of the 95 unit is substantially of the same cross-section as shown in Fig. 2. In this form the resistance is determined from the point 21 when the insulation is continued to the end.

100 In some instances flat end connections at both ends are desirable instead of the vertical terminals as shown in Fig. 1 and such a form is shown in Fig. 7.

105 The connection is accomplished by means of a metallic strip 24 being turned once around the wound resistance, and wound outwardly at a right angle as shown in Fig. 7. When the can and insulator are closed by the action of a die, it will be found that the strip 24 is very firmly secured within the element and will not easily pull out or become disengaged.

115 Thus, it will be seen that we have invented an electrical resistance unit, the size of which can be controlled by the number of turns per 120 inch on the base, or by variations in the diameter of wire used, or the combination in a single unit of several diameters of wire and windings in independent units, all centrally located within the completed electrical unit 130

for convenience in assembly and in repairing.

If desired, the assembled unit may be dipped into an impregnating solution which will serve, not only to assist in insulation, but to eliminate corrosion from salts and acids, and intrusion of foreign matter.

The resistance units of our invention are simple and economical of manufacture, efficient and permanent, all the parts being protected from foreign matter.

Although modifications may be made in the invention and modifications herein disclosed, we do not wish to be limited except as indicated in the appended claims.

We claim:

1. A resistance unit and voltage divider which comprises in combination, a resistance unit formed by winding a length of resistance wire over a non-conductive base, a plurality of projecting terminals located on said resistance unit in a predetermined spaced relation, a second resistance unit of similar construction placed in an end-for-end contacting relation to said first mentioned unit, an insulating jacket adapted to enclose said adjacent resistance units, and a metal can adapted to substantially cover said jacket and enclosed parts.

2. A voltage divider which comprises a pair of independent, wound resistance units placed in end-for-end relation, terminal clips secured to said resistance units in predetermined spaced relation, the terminal clips connected to one of said resistance units being independent from those connected to said other resistance units, an insulating jacket adapted to cover said wound wire and a portion of said terminal connections, and a metal can adapted to contain said jacket and enclosed parts.

3. A resistance device adapted to combine a plurality of fixed resistances comprising a length of non-conductive material adapted for use as a base, a length of resistance wire wound over the length of said base, the turns being in a predetermined spaced relation, terminal clips secured to said resistance wire at suitable locations thereon, said terminal clips being formed to provide an upstanding terminal, and the lower portion thereof being rebent to engage said resistance, an insulating shell adapted to receive said resistance and terminal connections, and a metal can adapted to receive said insulating shell and enclosed parts.

4. A resistance device adapted to combine a plurality of fixed resistances comprising a length of non-conducting material adapted for use as a base, a length of resistance wire wound over the length of said base, the turns being in a predetermined spaced relation, terminal clips secured to said resistance wire at suitable locations thereon, said terminal clips being formed to provide an upstanding

terminal, and the lower portion thereof being rebent to engage said resistance, another resistance unit provided with a plurality of terminal clips being disposed in an adjacent, independent end-for-end relation to said first mentioned resistance, an insulating shell adapted to receive said resistances and terminal connections, and a metal can adapted to receive said insulating shell and enclosed parts.

In testimony whereof we have affixed our signatures.
